UNITED STATES PATENT OFFICE

2,591,910

ELECTRON DISCHARGE AMPLIFIER DEVICE
EMPLOYING HOLLOW RESONATOR

Norman Charles Barford, Southend, England, assignor to Electric & Musical Industries Limited, Hayes, Middlesex, England, a company of Great Britain

Application October 18, 1946, Serial No. 704,225
In Great Britain September 10, 1945Section 1, Public Law, 690, August 8, 1946
Patent expires September 10, 1965

7 Claims. (Cl. 315—6)

1

This invention relates to electron discharge devices of the kind in which signals to be amplified are fed to a hollow resonator often termed a "buncher," tuned to the frequency of the signals which serves to impart velocity modulation to a beam of electrons projected through a gap formed therein, the velocity-modulated beam emanating from the buncher being then allowed to pass through a drift space in which the velocity-modulated beam becomes charge-density-modulated, after which the beam is caused to pass through a gap in a further resonator, frequently termed the "catcher," so as to impart energy thereto. Amplifier devices of this kind operating, for example, at about 3000 megacycles per second may have a bandwidth (between the half-power points) of about 10 megacycles per second. Such a relatively narrow passband may be undesirable in some cases and, accordingly, it is the object of the present invention to provide an improved electron discharge amplifier device employing hollow resonators in which the passband of the device as an amplifier is effectively increased.

According to the invention an electron discharge amplifier device of the kind referred to is provided in which one or more further resonators is or are arranged between the buncher and the catcher resonators so as to be traversed by the electron beam, said one or more further resonators being tuned to a frequency or frequencies slightly different from the frequencies to which the buncher and catcher resonators are tuned so as to increase the pass-band of the amplifier device.

In order that the said invention may be clearly understood and readily carried into effect, it will now be more fully described with reference to the accompanying drawings, in which:

Figure 1 is an explanatory curve;

Figure 2 illustrates diagrammatically an electron discharge device constructed according to one embodiment of the invention, and

Figures 3 and 4 are further explanatory curves.

The known form of electron discharge amplifier device hereinbefore referred to usually has a bandwidth (between the half-power points) of the order of 10 megacycles per second at frequencies around 3000 megacycles per second. In such an amplifier device the output/frequency response curve for a fixed power source of input would be similar to that indicated in Figure 1 of the drawings. In this case it will be seen that at the resonant frequency f_0 of the resonator maximum output is obtained whereas at frequencies removed from the resonant frequency a

smaller output is obtained. In accordance with the present invention one or more further resonators is or are arranged between the buncher and catcher resonators so as to be traversed by the electron beam of the device, such resonator or resonators being tuned to a frequency or frequencies slightly different from the frequency to which the buncher and catcher resonators are tuned. A typical form of electron discharge amplifier device embodying the invention is shown in Figure 2 of the drawings and comprises a cathode 1, a cathode shield 2, a toroidal first or buncher resonator 3, a toroidal output or catcher resonator 4, and a target 5, the envelope of the device being omitted. These two resonators function in the manner known in the art, input signals applied to the first resonator 3 via a coupling loop 6 and concentric line 7 causing the electron stream emanating from the cathode 1 and passing through the resonator 3 to become velocity-modulated and in the drift space between the resonator 3 and resonator 4 the velocity-modulated stream becomes charge-density-modulated and on passing through the resonator 4 imparts some of its energy thereto, energy being abstracted from this resonator via coupling loop 8 and concentric line 9. Two further toroidal resonators 10 and 11 are arranged between resonators 3 and 4 so as to be traversed by the electron beam, and these resonators are tuned to frequencies f_1 and f_2 , that is to say, to frequencies on either side of the frequency of f_0 to which the resonators 3 and 4 are tuned. If the resonators 3 and 4 are tuned to 3,000 megacycles, the resonators 10 and 11 may be to 2990 and 3010 megacycles respectively. The introduction of the additional resonators 10 and 11 serves to increase the bandwidth of the amplifier device and if only one intermediate resonator were employed the bandwidth of the amplifier device would be increased following the curve shown in Figure 3, whilst where two intermediate resonators are employed tuned respectively to frequencies f_1 and f_2 the bandwidth of the amplifier device would be along the lines of that shown in Figure 4.

It will of course be appreciated that the invention is not limited to the introduction of one or two intermediate resonators, since more than two intermediate resonators can be employed tuned to various frequencies removed from the resonant frequency of the buncher and catcher resonators. Further, it is not necessary where two intermediate resonators are employed to have a common wall for the two resonators as indicated in Figure 2.

What I claim is:

1. An electron discharge amplifier device comprising cathode means for generating and directing a stream of electrons along a beam path, input resonator means in said path adjacent said cathode means and tuned to a first frequency of the order of thousands of megacycles for velocity modulating said electrons, output resonator means in said path and spaced from said velocity modulating means and tuned to said first frequency for extracting oscillatory energy from said stream, and other means for increasing the bandwidth of said device comprising resonator means in said path intermediate said velocity modulating means and said energy extracting means and tuned to a second frequency differing from said first frequency by about ten megacycles.

2. An electron discharge device comprising cathode means for generating and directing a stream of electrons along a beam path, input resonator means in said path adjacent said cathode means and tuned to a first frequency for velocity modulating said electrons, output resonator means in said path and spaced from said velocity modulating means and tuned to said first frequency for extracting oscillatory energy from said stream, and means for increasing the bandwidth of said device comprising other resonator means in said path intermediate said velocity modulating means and said energy extracting means and including two cavity resonators tuned to frequencies slightly above and below said first frequency, respectively.

3. An electron discharge device according to claim 2, wherein said first frequency is of the order of thousands of megacycles and said frequencies differ therefrom by about ten megacycles.

4. An electron discharge device according to claim 2, wherein said cavity resonators have a common wall.

5. An electron discharge amplifier device comprising cathode means for generating and directing a stream of electrons along a beam path, a first cavity resonator tuned to a first frequency of the order of thousands of megacycles, a second cavity resonator tuned to a frequency differing from said first frequency by about ten megacycles, a third cavity resonator tuned to said

first frequency, and a collector electrode, said cavity resonators being apertured and arranged along said beam path between said cathode means and said collector electrode in the order named with said beam path extending through the apertures thereof.

6. An electron discharge amplifier device comprising cathode means for generating and directing a stream of electrons along a beam path, a first cavity resonator tuned to a first frequency, second and third cavity resonators tuned to frequencies slightly different from said first frequency, a fourth cavity resonator tuned to said first frequency, and a collector electrode, said four cavity resonators being apertured and arranged along said beam path between said cathode means and said collector electrode in the order named with said beam path extending through the apertures of the resonators.

7. An electronic amplifier comprising cathode means for producing a stream of electrons along a beam path, velocity modulating resonator means in said path adjacent said cathode means and tuned to a first frequency, output resonator means in said path and spaced from said velocity modulating resonator means and tuned to said first frequency, other resonator means in said path intermediate said velocity modulating resonator means and said output resonator means and tuned to a second frequency slightly different from said first frequency for increasing the bandwidth of said amplifier, means for coupling said velocity modulating resonator means to an input signal source, and means for coupling said output resonator means to a load, said resonator means being coupled together only by said stream of electrons.
